UNITED STATES PATENT OFFICE.

JAMES B. KNICKERBOCKER, OF INDIANAPOLIS, INDIANA.

GAS-METER.

SPECIFICATION forming part of Letters Patent No. 447,883, dated March 10, 1891.

Application filed July 11, 1890. Serial No. 358,460. (No model.)

To all whom it may concern:

Be it known that I, JAMES B. KNICKERBOCKER, of Indianapolis, county of Marion, and State of Indiana, have invented certain new and useful Improvements in Gas-Meters; and I do hereby declare that the following is a full, clear, and exact description thereof, reference being had to the accompanying drawings, in which like letters and figures refer to like parts.

My invention relates to the construction of meters for natural or artificial gas or other fluids, and will be understood from the following description.

In the drawings, Figure 1 is a longitudinal section of my device. Fig. 2 is a detail view of the outlet half of the meter, the diaphragm being removed and the casing partly broken away. Fig. 3 is a similar view to Fig. 1, showing the position of the parts when the valves have reached the limit of their movement on the right-hand side.

In detail my device comprises a casing made in two halves *c c'*, between which passes an elastic diaphragm *d*, having metal back-
25 ing-plates *m* on either side thereof, the whole connected together at the center by a bolt 15, sockets being cut through the ends of the bolt to receive the ends of the diaphragm-le-
vers *l*. On the outside of the casing is a hollow rim *w*, between which and the casing is a channel 10 for the passage of the gas. At either end of the casing are connections screw-threaded to receive pipes, *i* being the inlet
35 and *o* the outlet end. The passage-way on the inlet side has partitions 16 17 18, the former providing a seat for the valve *v*, which has open ports on either side and is connected to a stem *s*, the outer end of the valve pass-
40 ing through the partition 17, while the partition beyond the valve marked 18 has an opening closed by a screw-plug *c*², which when taken out will allow the removal of the valve, and a similar arrangement is found in the
45 outlet side of the machine. The valve-stem is connected to a stirrup-lever *l'*, whose ends pass about the valve-stem and bear against a button on the end, as shown in Fig. 2. To this stirrup-lever at 9 is connected the end of
50 a coiled spring *sp*, whose opposite end is connected at 5 to the axle of the diaphragm-lever *l*. This lever is provided with an arm

having a curved slot *sl*, which passes over a pin 1, connected with the stirrup-lever *l'*, and the movement of the diaphragm-lever *l* is limited by the length of this slot. The stirrup-lever is pivoted at 4 to a hanger 7, bolted to the inside of the casing. On the outlet side the valve *v'* has a similar stem *s*, about which a similar stirrup-lever *l'* passes, having a coiled spring connected at 9, the other end of the spring being pivoted to the axle of the diaphragm-lever on that side, which has a similar projection, with a slot passing about a pin in the stirrup-lever. The outlet-valve 65 is preferably somewhat different in construction from the inlet-valve, as shown in the drawings, and has seats in the walls 16 and 17, corresponding in function and in operation with those of the inlet side, the valve 70 working upon the outside of these walls instead of the inside, as shown in the other half of the machine.

r is the registering mechanism, having the usual dial and a toothed wheel 11, mounted 75 upon a shaft carried in the casing, and detents 2 and 3, engaging with the teeth of the wheel, a spring *sp'* connecting the two and holding them in position, these detents being pivoted to an arm which is formed in two 80 parts *a a'*, locked by a set-screw 22 to permit its adjustment as to length for regulating the stroke of the arm *a*.

The mechanism operates as follows: Gas being admitted through the inlet *i* passes into 85 the adjacent chamber and through the open outer end of the valve *v*, and up around the passage-way 10 and through the opening 19 into the chamber 13, which is on the outlet side of the diaphragm. Here the passage- 90 way of the gas is stopped, and it cannot escape through the outlet-valve *v'*, which is normally held closed by the action of the spring *sp*. As the pressure of the gas in the chamber 13 increases it pushes the diaphragm 95 to the right, and this throws the levers *l* in the same direction until the end 20 of the slot *sl* strikes against the pin 1 on the stirrup-lever *l'*, forcing it over until the connecting-point 9 of the spring *sp* passes beyond the 100 center of the pivot 4, when the tension of the spring automatically throws the lever still farther forward and outward, carrying the valve *v* from its seat in the partition 16 and

seating it on partition 17, preventing the gas from escaping through that end of the valve and opening the other end, so that the gas rushes through the ports of the inner end 5 of the valve into the chamber 14 on the inlet side of the diaphragm, thus counteracting the pressure upon the other side. At the same time the valve v' on the outlet side is operated in the same manner by the action of 10 the spring sp forcing the outlet-valve inward until it finds its seat against the partition 17, opening and releasing the opposite end of the valve from its seat in the partition 16, thus allowing the gas which has accumulated in 15 the chamber 13 to pass out through the ports of the valve to the outlet-pipe o . The pressure being thereby released on the outlet side of the diaphragm, the gas passes through the ports of the inner end of the valve upon the 20 inlet side, forcing the diaphragm back to the left, and the levers l reverse the previous movement of the stirrup-levers, forcing the valves in a contrary direction, thus maintaining a proper equilibrium. During this operation 25 the lever l in the chamber 13 on the outlet side of the diaphragm being pivoted to the shaft 5 operates the arm a , moving the detents 2 and 3, one of which pushes and the other pulls against the teeth of the wheel 11, 30 and of course each revolution of the wheel w is registered by an index-hand on the dial outside in the ordinary manner. When the gas enters the inlet i , it passes through the outer ports of the valve v in the direction of 35 the curved arrows and around the passage-way 10 through the upper opening 19 into the chamber 13 on the outlet side of the diaphragm. As the chamber fills, the diaphragm is forced to the left until it comes in contact 40 with the wall of the casing, as shown in Fig. 3, and the operative parts upon that side will be entirely clear of the chamber 14. Then through the operation of the spring sp the valve v is forced outward, finding its seat 45 on the partition 17, freeing it from its seat on the partition 16, thus opening a way for the gas through the valve-ports on the left-hand side for entrance into the chamber 14, cutting off the gas and preventing any 50 further inflow through the passage-way 10 into the chamber 13. While this movement is being accomplished a similar effect is produced upon the opposite side. The travel of the lever l , bringing the end 20 of the slot 55 against the pin upon the stirrup-lever l' , has brought the connecting-point 9 past the pivotal point 4. The spring sp has then exerted its force to throw the valve v' inward, seating it upon the outside of the partition 17 60 and freeing it from contact with the partition 16, closing the ports on the left-hand and opening those on the right-hand side of the valve, and the gas that has accumulated in the chamber 13 may then find its way through 65 the open ports on the right hand of the valve v up over the valve and out the pipe o . In other words, the entrance of the gas into the

chamber 14 displaces that in the chamber 13 its movement and direction being as hereinbefore mentioned.

The next movement in the operation of the machine is as follows: As the chamber 14 fills, the diaphragm is forced away from the right-hand wall of the casing and toward the left, carrying with it the levers l and their connections, effecting a reverse movement of the valves at the moment when the connecting-point 9 has been carried to the left of the pivotal point 4. The metal backing of the diaphragm on the left-hand side comes in contact with the wall of the casing, and the gas in chamber 14 finds its way through the lower opening 19 and around the passage-way 10, but it cannot yet escape, as the outer ports of the valve v' are closed and its further progress is checked until the pressure upon the inlet side of the diaphragm reverses the position of the valves.

It will be observed that the valves are controlled and held at all times by the springs sp , so that the diaphragm can be set vertically or horizontally, or even at an angle, and whether it is true or level makes no difference in the operation of the valves, they being always held in proper relation by the action of the springs sp .

The levers l connected on each side of the diaphragm operate simultaneously and in the same direction, the one operating the valve through the spring and its stirrup-lever on the inlet and the other on the outlet side, and as the gas enters the chamber the diaphragm is thrown clear over to the other side, so that the entire chamber of the casing is filled, the gas that had collected on the opposite side being displaced, and each movement of the lever in either direction is registered upon the dial, thus correctly gaging the flow. It is essential, therefore, to the operation of my machine that the diaphragm should be flexible, and that the levers l should be so disposed that they may be forced far enough to one side by the pressure of the gas upon the diaphragm to crowd the stirrup-lever connected with the valve-stem over beyond a vertical line, passing through the center of the pivot 4 and a point 9, where the spring is connected to the stirrup-lever, and that from this point the tension of the spring itself should automatically effect the movement of the valve, forcing it away from its hold against the seat in the partition-plates set in the chambers adjacent to the outlet and inlet pipes, and the arrangement of the mechanism producing this result is the principal feature of my invention. If the movement of the valve were directly actuated by the pressure of the lever controlled by the diaphragm, the result would be very different and the device would be irregular in movement and uncertain in result. In other words, the throw of the valve must not be directly effected by the movement of the diaphragm, but must at a certain point be instantaneously effected by a mechanism

independent of and not controlled by the gas-pressure, for if so controlled the result would be to open both valves and let the gas pass directly through the machine without operating the registering mechanism. This cannot happen in my device, for both the valves are controlled by the springs *sp*, and as one set of the valve parts are open the other are closed, and vice versa, and the pull of the spring *sp* is always against the pressure upon the diaphragm.

At 6 6 are openings closed by screw-plugs, one on each side of the diaphragm, to allow the removal of water, sediment, or dirt, which 15 might and often does accumulate in the outlet and inlet chambers, and such removal may be accomplished without interfering with the adjustment of the valves or the operation of the machine.

20 I am aware that meters have been constructed where bellows and pistons have been used for registering the flow of gas; but these are objectionable, for the bellows takes up too much room inside the machine, thus interfering with the operation of the working parts, and the displacement of the gas in the chamber is imperfectly accomplished, while the folds of the bellows by constant operation are injuriously affected and soon become 25 worn and liable to be ruptured, and no means are provided for cleaning or removing dirt or water from the apparatus without taking it apart, necessitating its removal from its connections and involving much delay, trouble, 30 and expense. All these objections are obviated in my meter, as I accomplish the result by the use of a single diaphragm or dividing-sheet and the displacement of the gas, and the division of the registered from the unregistered gas is effected without any strain upon the operative parts, and the action of the diaphragm under varying pressures is uniform on both sides.

What I claim as my invention, and desire 45 to secure by Letters Patent, is the following:

1. In a gas-meter, a casing composed of two equivalent parts, having outlet and inlet openings, and a single flexible diaphragm centrally secured therein, such casing provided with an 50 outer rim, whereby a channel for the passage of the gas through openings in the diaphragm is formed between the rim and the walls of the central diaphragm-chamber, substantially as shown and described.

55 2. In a gas-meter, a casing composed of two equivalent parts with inlet and outlet connections on opposite sides of such casing, a single flexible diaphragm centrally secured therein, outlet and inlet valves seated in partitions formed in the halves of the casing adjacent to the inlet and outlet openings, levers connected to the diaphragm on each side, and spring-actuated secondary levers connected to the valve-stems and adapted to be controlled 60 during a part of their movement by the diaphragm-levers and automatically controlled by the springs when such lever has

reached a certain point, such casing having a channel to permit the passage of the gas through openings in the diaphragm between 70 the inner wall of the casing and the wall of the diaphragm-chamber, all combined substantially as shown and described.

3. In a gas-meter, a casing having an exterior rim providing a channel-way between 75 the rim and casing for the passage of the gas, such casing divided into two parts, a single diaphragm secured between them dividing the central chamber, an inlet formed upon one side and an outlet upon the other side of 80 the casing, outlet and inlet valves seated in partitions formed in the ends adjacent to the outlet and inlet openings, and a pair of dia-phragm-levers connected on either side of the diaphragm and adapted to initiate the move- 85 ment of auxiliary levers pivoted to the in-terior walls of the casing and connected to the valve-stems at the other and controlled by a spring which automatically operates the valves when the action of the dia-phragm- 90 lever has carried the auxiliary lever beyond a certain point, in combination with a dial-registering mechanism connected to the cas-ing and actuated by one of the dia-phragm- 95 levers, all combined substantially as shown and described.

4. A gas-meter comprising a hollow casing composed of two similar halves having outlet and inlet openings on opposite sides of the casing, a single flexible diaphragm centrally 100 secured between the halves thereof, and outlet and inlet valves supported in partitions formed in the casing, their valve-stems connected to a stirrup-lever controlled by a coiled spring whose tension normally oper- 105 ates against the pressure upon the dia-phragm, substantially as shown and described.

5. In a gas-meter, a hollow casing having an outside rim forming a channel-way for the passage of the gas between the rim and the 110 casing, a single diaphragm dividing the cham- 115 ber and secured between the two halves of the casing, outlet and inlet openings, and valves arranged therein, the movement of such valves controlled by a spring connected to the stem, whose tension normally operates to resist the pressure of the diaphragm, in combination with levers connected to the dia-phragm and the casing provided with pro- 120 jections for initiating the movement of the spring-controlled stirrup-lever, and a register- 125 ing mechanism connected to the casing, all combined substantially as shown and de-scribed.

6. A gas-meter comprising a hollow casing 130 formed in two equal parts centrally connected to a single flexible diaphragm secured be-tween them, having outlet and inlet openings, and valves, the latter seated in walls formed in the interior of the casing, such valves actuated by the tension of a coiled spring connected through stirrup-levers to their stems, the movement of such stirrup-levers initiated through arms connected with the

diaphragm, whereby the final action of the valve is controlled by a spring independently of the further movement of the diaphragm, all combined substantially as shown and described.

7. In a gas-meter, a hollow casing composed of two equivalent parts having outlet and inlet openings, valves seated in walls formed in a casing adjacent to such outlet and inlet openings, and a single flexible diaphragm extending from side to side, dividing the hollow chamber of the casing, an exterior passage-way for the gas through openings in the diaphragm provided between the walls of the rim and those of the diaphragm-chamber, in combination with a dial-registering mechanism, substantially as shown and described.

8. A gas-meter comprising a hollow casing formed of two equal halves secured together and a single flexible diaphragm set between such halves, forming an inlet-chamber upon one side of such diaphragm and an outlet-chamber upon the opposite side, such casing

provided with an exterior passage-way for the gas between the walls of a rim and those of the casing, substantially as shown and described.

9. A gas-meter comprising a hollow casing formed of two similar halves secured together and a single flexible diaphragm set between such halves, whereby an inlet-chamber is formed upon one side thereof and an outlet-chamber upon the opposite side, such casing provided with an exterior passage-way for the gas between the walls of the central diaphragm chamber and the outer wall of the casing, such diaphragm perforated to admit the passage of the gas through such channel and through the diaphragm, substantially as shown and described.

In witness whereof I have hereunto set my hand this 1st day of July, 1890.

JAMES B. KNICKERBOCKER.
